United States Patent Office

Des. 195,656

Patented July 9, 1963

195,656

MORSE CODE SIGNALLING LIGHT

Charles L. Cleek, Pacific Palisades, Calif.
(1540 Sagebrush Road, Palm Springs, Calif.)

Filed Oct. 8, 1962, Ser. No. 72,018

Term of patent 14 years

(Cl. D72—1)

FIG. 1.

FIG. 2. FIG. 3.

FIG. 5.

FIG. 4.

FIGURE 1 is a perspective view of a Morse code signalling light showing my new design.

FIGURE 2 is a top plan view thereof.

FIGURE 3 is a front elevational view of FIGURE 1.

FIGURE 4 is a side elevational view thereof.

FIGURE 5 is a rear elevational view thereof.

The undisclosed side is substantially the same in appearance as the side shown.

I claim:

The ornamental design for a Morse code signalling light, as shown and described.
